UNITED STATES PATENT OFFICE.

JOSEPH COURVILLE, OF DETROIT, MICHIGAN, ASSIGNOR, BY MESNE ASSIGNMENTS, TO
BUSH AND LANE PIANO COMPANY, OF CHICAGO, ILLINOIS, A CORPORATION OF
ILLINOIS.

PNEUMATIC ACTION.

1,164,632.

Specification of Letters Patent. Patented Dec. 21, 1915.

Application filed December 27, 1913. Serial No. 808,949.

To all whom it may concern:

Be it known that I, JOSEPH COURVILLE, a citizen of the United States of America, residing at Detroit, in the county of Wayne 5 and State of Michigan, have invented certain new and useful Improvements in Pneumatic Actions, of which the following is a specification, reference being had therein to the accompanying drawings.

10 The invention relates to pneumatic actions particularly designed for use in connection with percussion musical instruments, such as automatic pianos.

It is the primary object of the invention 15 to simplify the construction, dispensing with parts usually employed, and at the same time obtaining a sensitive and quickly responsive construction.

It is a further object to condense the structure within small space limits without crowding or interfering with the function of any of the elements.

To this end the invention comprises various features of construction as hereinafter 25 set forth.

In the drawings: Figure 1 is a cross section through a portion of the action showing one of the individual pneumatics; Figs. 2 and 2^a are perspective views of the parts 30 forming the valve case detached; and Fig. 3 is a plan view partly in horizontal section of one of the power pneumatics with the valve case detached.

In the construction of pneumatic actions 35 for musical instruments, it is usual to employ a system of primary, secondary and power pneumatics, which relay the primary air currents controlled by the music sheet and tracker, and furnish the necessary 40 power for operating the sound producer. The use of this triple system increases the complexity of the structure while it is nevertheless deemed necessary to secure both power and speed. I have devised a construction 45 in which the intermediate pneumatics are dispensed with without sacrificing either power or speed, the construction being as follows:

My improved action preferably comprises 50 a plurality of superposed tiers of pneumatics connected to a common wind chest. This wind chest is preferably formed of horizontally-extending tubes A, one for each tier, with spaces B therebetween for receiving a

portion of the power pneumatics C. Each 55 of these pneumatics is assembled with a co-operating controlling valve and primary pneumatic, constituting therewith a unit independently attachable to and detachable from the wind chest. The outer pneumatic 60 C is preferably of the bellows type, being provided with a stationary board D and movable board E. The stationary board is preferably rabbeted or cut adjacent to the hinge end to form a shoulder F for seating 65 against the tube A. This board is also formed with a recess G therein for the primary valve pouch H, and at one side of this recess is a bore J extending out through the end of the board and connected with the tube 70 K leading to the tracker for the primary air current. Adjacent to the board D is a valve chest, preferably formed of metal and in two sections L and M. The section L is formed with a complementary recess N for the valve 75 pouch, having a central through aperture for the valve stem. This valve stem O has a head P at its lower end for engaging the button or central plate Q on the pouch G.

R is a valve mounted on the stem O and 80 located in a recess S formed in the outer member M of the valve chest. The recess S has a through aperture T in alignment with the through aperture in the lower section of the chest, and the valve is of greater diameter 85 to seat upon the marginal portions surrounding said apertures. There is also an extension U of the recess S, which communicates with an aperture V extending 90 through the lower section of the chest and the board D, so as to communicate with the interior of the power pneumatic. The section L has a port W through the end adjacent to the tube A, and which registers 95 with a port in said tube so as to establish communication between the valve cell N and the wind chest. There is also a bleed port X formed in a diaphragm X' above the board D, and communicating with a lateral port in the bore J. The recess N is enlarged 100 to extend over the bleed X, thereby establishing a constant connection with the vacuum of the chest.

The sections L and M of the valve chest are secured in position by screws Y extending 105 through marginal registering apertures therein and into the top board D of the power pneumatic. These sections are also

secured to the tube A by screws Z passing through said tube and engaging threaded apertures in the respective sections, the heads of said screws being upon the outside of the 5 tube A and packing washers G' being employed to seal the joint.

With the construction as described whenever vacuum is created within the tube A it will be communicated to the chamber N of 10 the valve cell and through the bleed X to the registering chamber below the pouch H. This will equalize the pressure upon opposite sides of said pouch and will permit the valve R to rest upon its lower seat, closing 15 the port N' between the lower and upper sections of the chest and opening the port T communicating with the atmosphere. This will cause atmospheric connection with the chamber S in the upper section of the valve 20 case, and through the port V with the chamber within the power pneumatic C. Whenever a primary air current is admitted through the tube K by the registration of a port in the music sheet with the tracker port, 25 this will admit air under atmospheric pressure below the pouch H, raising the same and causing it to lift the valve stem O and valve R, thereby opening the port N' and closing the port T. This will place the vacuum 30 upon the chamber S and the port V, collapsing the pneumatic C and causing it to deliver the power stroke.

To guide the valve R and hold the same from lateral displacement a series of pins R' 35 are arranged around the same, being secured to the lower section L of the chest. Air tight joints are formed by compressible facings or gaskets between the faces of the several sections.

What I claim as my invention is:

In a pneumatic action, the combination of a power pneumatic of the bellows type having a recess in the stationary wall thereof, and a port distinct from said recess to the interior of the pneumatic, a pouch covering 40 said recess, a wind chest, means for securing the wind chest to the pneumatic, two metallic valve sections of substantially the same contour superimposed one upon the other and said power pneumatic, and having their 45 ends abutting against the side of the said wind chest, one of said valve chest sections being recessed to form a chamber for the pouch, and a port for registration with the power pneumatic port, and the other section 50 being recessed to form a valve chamber communicating with said power pneumatic and with the external atmosphere, a fastening member passing through said sections exteriorly of the chamber of the valve chest at 55 its upper end and engaging the stationary wall, securing said valve chest to said wall, the stationary wall of the power pneumatic being provided with a horizontally extending bore adjacent the lower portion of the 60 wind chest and a vertically extending bleed passage leading from said bore and communicating with said chamber from the pouch, and a diaphragm provided with a 65 port therein overlying said vertically extending bleed passage, substantially as described.

In testimony whereof I affix my signature in presence of two witnesses.

JOSEPH COURVILLE.
